UNITED STATES PATENT OFFICE

2,440,405

COMBUSTION RESPONSIVE FUEL CONTROL

Roy W. Johnson, Milwaukee, Wis.

Application August 31, 1944, Serial No. 552,168

5 Claims. (Cl. 158—28)

1

This invention relates to improvements in devices for controlling the flow of fuel to a burner and particularly to means for closing the inlet valve of such devices if the burner flame is not ignited or is extinguished for any reason.

One of the objects of the present invention is to provide a fuel flow control device in which the inlet valve thereof is closed upon failure to ignite fuel supplied to a burner or upon extinguishment of the fire after ignition thereof.

Another object of the invention is to provide fuel flow control means in which the inlet valve is automatically closed responsive to the temperature of the burner.

Another object of the invention is to provide temperature-responsive means for controlling the flow of fuel to a burner, which means will interrupt such fuel flow after a time lapse insufficient to flood the burner in case the fuel is not consumed.

Another object of the invention is to provide means acting automatically after manual starting thereof for controlling the flow of liquid fuel to a burner of the pot type in which presence of a fire in the pot allows the fuel flow to continue and the absence of a fire shuts off the fuel flow before a sufficient time has elapsed for flooding the pot.

Another object of the invention is to provide simple means which may be readily combined with a liquid fuel flow control device of the constant level type for preventing flooding of a heater burner by controlling the inlet valve for such devices free from interference with the normal control means for the inlet valve or with other safety shut-off means for such valves.

A further object of the invention is to provide a safety shut-off device for mechanisms controlling the flow of liquid fuel to a burner in which the device is simple in its construction, reliable and durable in operation, and easy and inexpensive to manufacture and install and which may be added to many of such mechanisms now in use.

Objects and advantages other than those above set forth will be apparent from the following description when read in connection with the accompanying drawing in which:

Fig. 1 is a vertical sectional view through a liquid fuel flow control means of the constant level type embodying the present invention and with a fragment of a fuel burning pot to show the structural relationship of the pot with a structure embodying the present invention;

Fig. 2 is a top plan view of a board bearing the terminals to which the electrical portions of

2

the present device are connected and on which some of such electrical portions are mounted:

Fig. 3 is a bottom plan view of the terminal board on which portions of the electrical elements of the present invention are mounted;

Fig. 4 is a fragmentary view partially in section showing the construction of one of the electrical elements of the device;

Fig. 5 is a diagrammatic view showing the interconnection of the electrical elements of the present invention; and

Fig. 6 is an enlarged detailed view of portions of the structure illustrated in Fig. 1 and shown diametrically in Fig. 5.

15 Referring to the drawing by reference numerals, the numeral 6 designates a casing defining a main chamber 7 to which liquid fuel flows by way of an inlet conduit indicated at 8 and an inlet passage in the main chamber under the control of an inlet valve which comprises a tubular valve casing 11 placed in the inlet passage and formed with discharge passages transverse to the axial passage and with an interior shoulder forming a seat for a valve 12. The inlet valve 12 is shown as being of the needle type slidably fitting in the upper portion of the valve casing 11 and as having an exteriorly threaded, flanged sleeve 13 secured on the upper portion thereof. A flanged member 14 seats on the flange of the sleeve 13 and provides a seat for a spring 15 compressed against the spring seat 14 by a washer 16 and a nut 17 threaded on the sleeve 13, the spring 15 serving as means for retaining the nut 17 in a predetermined position. The valve casing 11 is surrounded by a spring 18 acting between a shoulder on the valve casing and the underside of the spring seat 14 to bias the valve upwardly away from its seat and into an open position.

40 The degree to which the inlet valve 12 is opened by the spring 18 is determined by a float 21 having a lever 22 extending therefrom and pivotally mounted intermediate its ends on a bracket 23 in the casing 6, the end of the lever beyond the pivoting point thereof being bifurcated and bearing on the washer 16 on two sides of the nut 17. Thus, rise in the level of the liquid in the chamber 7 rocks the float 21 about its pivot so that the end of the lever bearing on the washer 16 pushes the inlet valve toward the closed position as the liquid level rises. Above a predetermined level in the chamber 7 the float 21 completely closes the inlet valve during normal operation of the device.

45 However, even though precautions are usually

taken to supply only fuel free from grit, etc., the inlet valve 12 may be held off its seat for some reason in spite of the action of the float 28 in urging the valve toward its seat. Under such circumstances the level of the fuel in the chamber 7 continues to rise until the fuel flows over a partition 26 extending across the casing 6 and forming an auxiliary chamber 27 which contains a float 28. The auxiliary float 28 is pivotally connected with a lever 29 also pivotally mounted on the bracket 23 and having the end thereof adjacent the pivot formed to act as a latch for a mechanism for forcibly closing the inlet valve upon release of the mechanism. The valve-closing mechanism includes a plate member 32 pivoted on the bracket 23 and formed with a handle 33 extending outside of the casing 6 and with an extension bearing a weight 35 in the chamber 7. A spring 36 interconnects the bracket 23 and the plate 32 to assist the weight 35 in biasing the plate 32 downwardly for contact with the nut 17 and hence the valve 12. When the auxiliary float 28 is positioned as shown in Fig. 1 in the drawing, the end of its lever 29 engages the plate 32 and latches the plate in raised position against the downward biasing of the weight 35 and the spring 36. If the inlet valve 12 sticks in open position, the liquid level in chamber 27 raises the float 28 to release the end of its lever 29 from the plate 32. The weight 35 and the spring 36 then snap the plate 32 downwardly to strike on the nut 17 and to force the inlet valve 12 into closed position.

Fuel is supplied from the main chamber 7 by way of a conduit 41 to a pot or other fuel-burning device indicated at 42, under the control of a metering valve, generally indicated herein at 43, and preferably such as disclosed for example in Patent 2,293,903, granted to me on August 25, 1942, in which a tubular guide with an internal seat is fitted into an outlet passage in the casing 7 to receive a tubular valve slideable in the guide and controlling the flow of fuel by means of a slot through the valve, which slot is exposed to the fuel in the supply chamber above the metering valve guide seat. The metering valve is biased toward open position by a spring 44 to a degree which may be determined by adjusting a manually operable knob 45 acting, through a cam structure, disclosed in the above patent, on a pin 46 in vertical alignment with the metering valve 43, as is also described in the above patent.

The position of the metering valve 43 may also be controlled by thermostatically operated means acting on the valve through a leverage now to be described. A pin 50 extends through the top of the casing 6 and, at its lower end, has a head resting on one arm 51 of a lever pivotally mounted in the casing and having a second arm, designated 52, and offset to one side of the arm 51. The lever arm 51 overlies an arm 53 of stiffly resilient material fixed at one end in the casing, as indicated at 54, and engaged near its other end by an adjusting screw 55 so mounted in the casing as to be capable of swiveling in its seat. The adjusting screw 55 flexes the arm 53 upwardly or downwardly so that variations in grade of the fuel may be compensated. The lever arm 52 is provided at its free end with a threaded opening receiving a slotted screw 56 bearing on the free end of the resilient arm 53 to compensate for changes in oil viscosity and thus determine the low or pilot-fire position of the metering valve. The lever arm 52 also has a leaf spring

57 connected thereto and extending over the end of the metering valve 43 and engaging therewith under certain adjustments of the above leverage. A bimetallic strip 58 is also fixed at one end to the end of the lever 52 bearing leaf spring 57 and underlies such spring. The bimetal modifies the action of the spring in response to temperature changes and thus compensates for oil viscosity changes due to temperature changes.

10 In the manual control of the metering valve 43, the knob 45 is adjusted to extend the pin 46 through a hole in the lever arm 52 until the pin bears on the spring strip 57 through which the pin acts on the metering valve to adjust the position thereof. Such adjustment of the valve may be continued until the lever arm 52 brings the screw 56 into engagement with the end of the resilient arm 53 to the low or pilot-fire position determined by adjustment of the screw 56. 15 Further adjustment of the knob then flexes spring 57 to close metering valve 43 completely at which time the spring also rests on bimetal 58.

20 The valve-operating leverage above described is actuated by a controlling unit mounted on the casing 6 and acting on the pin 50. A control 25 casing bottom portion 60 is mounted on the main casing 6 and supports a terminal board or panel 61 preferably of both electrical and heat-insulating material spaced from the control casing bottom 60. The terminal board is provided with a plurality of terminals 62 to 67, inclusive, for connection with electrical conductors and has mounted on the upper surface thereof a transformer 68. A heat motor preferably comprising 30 a bimetallic strip 71 and an electrical heating element 72 of any suitable type, mounted in heat-conducting and electrical insulating relation on the bimetal 71, is secured on the under side of the board 61 and preferably in heat-insulated 35 relation, as indicated at 73. The bimetal 71 has fixed on one end thereof an extension 74, which is preferably of heat-insulating material, for engaging the pin 50. The portion of the extension beyond the casing 60 is partially enclosed 40 by a guard 75 to prevent interference with movement of the heat motor. And the entire control 45 unit is covered by a top casing 76 fitting over the bottom casing 60.

50 A second heat motor, including a bimetallic strip 78 and a heater 79, is fixed on the under side of the terminal board 61, as at 80. The bimetal 78 extends over the inlet valve 12 in such 55 position as to be engageable with an extension 81 from the valve, and the end of the bimetal extends into a position such that the curled end thereof may engage a notch 85 in a lever 82 to serve as a latch for holding the lever in predetermined position so long as the bimetal is cold. The lever or handle 82 carries a contact 83 engageable with a contact 84 mounted on the terminal 60 board, the two contacts forming a starting switch for some of the electrical elements of the device, as will appear hereinafter.

65 In addition to the switch 82, 83, 84 controlling energization of portions of the electrical elements of the device, a thermostat is provided, as is diagrammatically indicated at 90 in Figure 5, for mounting in a space in which the temperature is to be controlled, and operating in conjunction 70 with a thermally actuated limit switch. The limit switch, which is preferably formed as a bimetallic strip 91 is fixed, as at 92, on the burner pot 42 with an electrical contact 93 mounted on the strip and a cooperating contact 94 fixed on the 75 side of the pot. Electric current is supplied to the

electrical elements of the device from a suitable power line, designated at 96 and indicated as being the usual 110-volt line available in residences. It will be understood, of course, that current may also be supplied to the usual hot-air circulating fan or a draft fan (not shown) by way of connections 97.

The interconnections of the various elements forming the electrically energized portions of the device, and the action of the heat motors, can be best seen by reference to the diagram in Fig. 5. The transformer 68 is always connected to the electric line 96 and is always energized. Consequently, closure of the thermostat 90, when more heat is required, completes a circuit through the heater 72 which heats the bimetal 71 to warp the extension thereof up from the pin 50. Such pin lifts upwardly to permit the metering valve 43 to supply more fuel. The terminals of the transformer 68 are severally connected through bimetallic strip 91 to contact 93 and to contact 94. If the temperature of the pot 42 rises to a sufficient value, the bimetal 91 warps to close contacts 93 and 94 which complete a circuit through the heater 79 to heat the bimetal 78 which is designed to warp upwardly away from the inlet valve extension 81 when heated and to flex toward the valve extension when cooled. The notch 85 in the starting switch handle 82 is engageable with the end of the bimetal 78, as shown in Fig. 5, when the switch is closed, and disengages from such handle when the switch is opened, as shown in Fig. 6.

The operation of the device will be clear from the following description. The inlet valve closing member 32 is raised by lifting the handle 33. The chamber 28 then being empty, the float lever 29 latches the plate 32 in raised position. The spring 18 can then open the inlet valve 12 and fuel flows into the chamber 7 under the control of the float 21. The switch handle 82 is lifted to close the contacts 83, 84 so that electric current flows from the transformer 68 through the heater 79 to commence heating the bimetal 78.

Contacts 83 and 84 are held closed by engagement of the end of the bimetal 78 in the notch of the handle 82 so long as the bimetal is below a predetermined temperature. The metering valve 43 is then manually set to a position so that oil may flow to the pot 42 at a desired rate where it is ignited to maintain a desired temperature in the space to be heated. As soon as the pot 42 reaches a predetermined temperature, the thermal switch contacts 93, 94, close to complete another circuit to the heater 79. As soon as the bimetallic 78 is sufficiently heated to warp upwardly and release the switch handle 82, the handle drops to open the circuit completed by the contacts 83, 84. The device is now in full operation with the thermal switch 91, 93, 94 controlling the heater 79 and actuating the bimetal 78.

If all of the above described starting steps are performed excepting igniting of the oil in the pot 42, closure of the switch 82, 83, 84, with the latching thereof by the bimetal 78, causes the heater 79 to warp the bimetal 78 upwardly which releases switch handle 82 and allows the starting switch to reopen. The bimetal 78 then cools and pushes the inlet valve to closed position before the pot can be flooded. If the fuel in the pot 42 is extinguished for any reason, the thermal limit switch 91, 93, 94 opens and the heater 79 cools down so that the bimetal 78 returns to the position shown in Fig. 1 and presses the inlet valve 12 towards closed position until the starting

switch 82, 83, 84 is again lifted. It will be apparent from the above description that the fire pot cannot be flooded, either by failure to ignite the oil supplied thereto upon starting of the system or by extinguishment of the fire after starting, for any reason whatever.

Although but one embodiment of the present invention has been illustrated and described, it will be apparent to those skilled in the art that various changes and modifications may be made therein without departing from the spirit of the invention or from the scope of the appended claims.

I claim:

- 15 1. In a device for controlling the flow of fuel to a burner, an inlet valve controlling the supply of fuel and biased toward open position, a bimetallic element movable into position to close the valve, an electric heating element for supplying heat to warp the bimetallic element away from valve-closing position, a plurality of circuits for supplying electric current to the heating element, a manually operable switch closing one of the circuits to the heating element, the bimetallic element engaging and retaining the manually operable switch in closed position for a predetermined time after energization of the heating element, and a thermally responsive switch for closing another of said circuits to the heating element to hold the bimetallic element out of valve-closing position after opening of the manually operable switch, the thermally responsive switch closing on combustion and opening upon non-combustion of fuel in the burner.
- 20 2. In a device for controlling the flow of fuel to a burner, an inlet valve for controlling the supply of fuel and biased toward open position, a bimetallic element movable into position to close the valve, an electric heating element for supplying heat to warp the bimetallic element away from valve-closing position, a plurality of circuits for supplying electric current to the heating element, a switch having a manually operable handle and closing one of the circuits to the heating element, the bimetallic element engaging the handle of the switch for latching the same in closed position for a predetermined time after energization of the heating element, and a switch mounted on the burner and responsive to the temperature thereof resulting from continued combustion of fuel therein for closing another of said circuits to the heating element whereby the bimetallic element is held out of valve-closing position after opening of the manually operated switch.
- 25 3. In a device for controlling the flow of fuel into a burner, an inlet valve urged toward an open position and controlling the flow of fuel into the device, a thermally responsive element urging the valve toward closed position when unheated, an electrically energized heater moving the element out of valve closing position when energized, a pair of electric circuits for energizing the heater upon closure of either of the circuits, a manually closed switch controlling one of the circuits, the manually closed switch being engaged by and released for automatic opening after predetermined movement of the thermally responsive element, and a hot-closed combustion-responsive switch controlling another of the circuits and opening responsive to temperature changes resulting from interruption of fuel combustion in the burner.
- 30 4. In a device for controlling the flow of fuel into a burner, an inlet valve urged toward open

position and controlling the flow of fuel into the device, a thermally responsive element urging the valve toward closed position when unheated, an electrically energized heater moving the element out of valve closing position when energized, a plurality of electric circuits for energizing the heater upon closure of any one of the circuits, a manually closed and gravity opened switch controlling one of the circuits, the end of the thermally responsive element engaging and holding the switch closed for a predetermined time after energization of the heater, and a hot-closed combustion-responsive switch controlling another of the circuits and opening responsive to temperature changes resulting from interruption of fuel combustion in the burner.

5. In a device for controlling the flow of fuel to a burner, an inlet valve biased toward open position and controlling the flow of fuel into the device, a heat motor urging the valve toward closed position when deenergized, a plurality of electric circuits for supplying energy to the motor for actuation thereof, a manually actuated switch controlling the closing of one circuit, the switch being held closed by the heat motor for a predetermined time after energization and

opening a predetermined time after deenergization thereof, and a switch responsive to the temperature resulting from combustion of fuel in the burner and controlling another circuit for continuing energization of the heat motor upon opening of the manually actuated switch, the temperature responsive switch opening upon non-combustion of fuel.
